FRANK RÀCZ, OF COATESVILLE, PENNSYLVANIA.

EXTINGUISHING ATTACHMENT FOR LAMP-BURNERS.

1,369,126.

Specification of Letters Patent. Patented Feb. 22, 1921.

Application filed September 8, 1920. Serial No. 408,934.

To all whom it may concern:

Be it known that I, FRANK RÀCZ, citizen of Hungary, residing at Coatesville, in the county of Chester and State of Pennsylvania, have invented certain new and useful Improvements in Extinguishing Attachments for Lamp-Burners, of which the following is a specification.

This invention relates generally to lamp burners, having more particular reference to an attachment adapted to be applied to the burner whereby the latter may be extinguished and the smoke from the extinguished wick prevented from escaping.

15 The invention has for an object to provide a novel and simple attachment for a lamp burner which operates as above set forth.

For further comprehension of the invention, and of the objects and advantages 20 thereof, reference will be had to the following description and accompanying drawings, and to the appended claims in which the various novel features of the invention are more particularly set forth.

25 Figure 1 of the drawings is a horizontal sectional view of a lamp burner having the invention applied thereto, this view being taken on the line 1—1 of Fig. 2.

Fig. 2 is a vertical sectional view on the 30 line 2—2 of Fig. 1.

Fig. 3 is a vertical sectional view on the line 3—3 of Fig. 2, this view being taken at right angles to Fig. 2.

My improved attachment may be applied 35 to any burner of ordinary construction, the numeral 10 indicating the base of the burner, 11 the wick-tube, 12 the wick feed rod and 13 the dome, while 14 indicates the usual horizontal top member of the base. A portion 40 of the bowl of a lamp is indicated in dot and dash lines at 15, and of the chimney at 16.

My improved attachment comprises a pair 45 of complementary hood elements which are arranged to jointly fold over the wick tube 11 while closely engaging the sides of the latter at their lower ends to prevent escape of the smoke.

Each of these hood elements comprises a 50 flat shutter 18 which is of a length as great as the width of the wick tube and is hinged at one end to the latter as at 19 a short distance below the upper end thereof. The free ends or edges of these shutters may be 55 very curved as shown in Fig. 1 while a laterally projecting flange 20 is formed on

each of the shutters which extends around this concavely curved edge and the adjacent sides of the shutter. It is to be understood that the parts are so proportioned that 60 when the shutters are thrown upward to the position indicated in dot and dash lines in Fig. 2 the shutters 18 will be flat against the sides of the wick tube while the projecting flange on one of the shutters will fit 65 snugly within the flange on the other shutter, the flange which fits within the other being shortened as shown in Fig. 2.

The means by which these shutters are operated is as follows: Formed on the backs 70 of the shutters are a pair of T-guides 25 which extend radially of the burner and in each of these guides is freely engaged a T-head 26, these T-heads being fixed on the upper ends of a pair of arms 27 which are 75 here in the form of angular extensions from a pair of rods 28 which extend along on opposite sides of the wick feed rod 12 and are rotatably supported in brackets 29 carried by the latter. These rods 28 have handles 80 30 fixed to their outer ends. It is to be understood of course that the horizontal partition member 14 will be suitably slotted to permit of movement of the arms 27.

It is believed that the manner of operation 85 of my improved attachment will be apparent from the above description. By pressing upon the handles 30 to swing them toward one another the arms 27 will be correspondingly swung, and since the heads 26 on 90 the ends of these arms normally engage the outer ends of the guides 25, the inward movement of the arms will cause the shutters 18 to be swung up into operative position. The flanges 20 on the shutters preferably 95 engage each other with sufficient frictional force to retain the shutters in their operative position until the handles 30 are again pushed apart, so that the end of the wick may remain inclosed to prevent escape 100 of the smoke.

Having thus described my invention what I claim as new and desire to protect by Letters Patent of the United States is as follows:

1. A device of the class described comprising, in combination with the wick tube of a burner, a pair of shutters hinged to said wick tube on opposite sides thereof and having angular marginal flanges adapted to engage 110 within each other, and means for swinging said shutters upon their hinges,

said means including T-guides formed on the said shutters, and rotatable arms having T-heads slidably engaging in the said guides.

- 5 2. A device of the class described comprising, in combination with the wick tube of a burner, a pair of shutters hinged to said wick tube on opposite sides thereof and having angular marginal flanges adapted to 10 engage within each other, and means for swinging said shutters upon their hinges, said means including a pair of T-guides formed on the backs of said shutters, heads 15 engaging freely in said guides, arms on which said heads are mounted rods on which said arms are fixed, and handles on said rods for rotating the same.

3. A device of the class described com-

prising, in combination with the wick tube of a burner, a pair of shutters hinged to 20 said wick tube on opposite sides thereof and having angular marginal flanges adapted to engage within each other, and means for swinging said shutters upon their hinges, said means including a pair of T-guides 25 formed on the backs of said shutters, heads engaging freely in said guides, arms on which said heads are mounted rods on which said arms are fixed, and handles on said rods extending along opposite sides and being supported by, the wick feed rod of the burner.

In testimony whereof I have affixed my signature.

FRANK RÁCZ.
